UNITED STATES PATENT OFFICE.

JOSEPH H. LA ROUCHE, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SOLE-PRESSING MACHINE.

1,274,723.

Specification of Letters Patent. Patented Aug. 6, 1918.

Application filed March 11, 1911. Serial No. 613,703.

To all whom it may concern:

Be it known that I, JOSEPH H. LA ROUCHE, a citizen of the United States, residing at Lynn, in the county of Essex and State of 5 Massachusetts, have invented certain new and useful Improvements in Sole-Pressing Machines; and I do hereby declare the following to be a full, clear, and exact description of the invention, such as will enable 10 others skilled in the art to which it appertains to make and use the same.

This invention relates to sole-pressing machines and more particularly to such machines of the type in which a shoe sole, constituting a portion of a lasted shoe, is conformed to the shape of the bottom of the last by the action of coöperating pressing instrumentalities such as a jack and a form, or mold. Machines of the general type in 20 question are commonly designated as sole-laying machines, or as direct-pressure sole-leveling machines, according to the steps in the manufacture of the shoe in connection with which they are used.

25 Owing to the great variety of styles and sizes of shoes and the corresponding varieties in the lasts which are employed in connection with machines of the type described, such machines are commonly provided with adjusting devices by which they may be adjusted to produce similar effects upon all soles whatever the style and size of the shoe being operated upon. Such means usually is arranged to vary the initial distance between the pressing instrumentalities, 35 while the mechanism for moving the latter is arranged to impart pressing movements of uniform amplitude.

The object of the present invention is to 40 produce a machine of novel and simple construction in which preliminary adjustment of the sole pressing mechanism is dispensed with in changing from one class of work to another. In accordance with this object a 45 feature of the invention comprises provision for accommodating itself automatically to lasts and shoes of varying sizes, in so far as the production of a predetermined degree of pressure upon the work is concerned. In the best form of the invention 50 at present known to the inventor, this end is accomplished by making the relative movement of the pressing instrumentalities toward each other variable in extent, the ac-

tuating mechanism being arranged to continue such movement until the work has been subjected to a predetermined pressing action and then at once to discontinue, automatically, the relative movement of the pressing instrumentalities. 55

60 Other objects and features of the invention, readily understood by those skilled in the art, will be set forth in connection with the following description of the embodiment thereof illustrated in the drawings and 65 then definitely pointed out in the appended claims.

In the accompanying drawings Figure 1 is a front elevation of a sole-laying machine embodying the present invention, with a 70 portion of the casing broken away to show the interior mechanism;

Fig. 2 is a side elevation of the machine, looking from right to left in Fig. 1;

Fig. 3 is a rear elevation of the lower right 75 hand portion of the machine; and

Fig. 4 is a vertical section, on a larger scale than the preceding figures, of the lower portion of the machine, looking from right to left in Fig. 1, and taken substantially on 80 the line 4—4 in said figure.

The invention, as illustrated, is embodied in a sole-laying machine in which the sole-pressing instrumentalities comprise a jack, upon which a lasted shoe may be mounted, 85 and a coöperating form. The jack, as illustrated particularly in Fig. 1, comprises a cross-head 5 having ways 6 and 7 upon which a heel-post 8 and a toe-post 9 are adjustably secured. The heel-post and the toe- 90 post may be of any ordinary or suitable construction, and they are adapted to support a lasted shoe 11, in the usual manner, above the vertically reciprocating form 12.

The cross-head 5 is mounted to slide vertically for a limited distance, on vertical rods 13 constituting a part of the frame of the machine. The cross-head normally rests, however, upon collars 15 fixed on the rods 13. Upward movement of the cross-head is 100 resisted by compression springs 16 bearing upon the cross-head and engaging at their upper ends a yoke 17 which is vertically adjustable upon the rods 13. The yoke is supported against the pressure of the springs 105 by means of a screw 18 which is splined so as to slide, but not to rotate, in a cross-bar 14 fixed to the upper ends of the rods 13. The

vertical position of the screw 18 is controlled by a nut mounted in a recess in the cross-bar having at its periphery a worm-wheel 19. This worm-wheel is in mesh with a worm 21 journaled in the cross-bar and rotatable by means of a hand wheel 22. By the means just described, the degree of compression of the spring 16 may be adjusted so as to regulate the downward pressure by means of which the jack is held against the collars 15.

The form 12 is mounted in any ordinary or suitable manner upon a bed 23 of usual construction which slides vertically upon the rods 13. The bed is actuated in a well known manner, by means of a toggle comprising arms 24 and 25, as shown particularly in Fig. 4. The arm 24 is pivoted to the bed 23, while the arm 25 is pivoted to a fixed portion 26 of the frame of the machine. The toggle is straightened and bent by means of a pitman 27 which connects the central joint of the toggle with a crank 28. This crank is fixed upon a crank-shaft 29 journaled in the frame of the machine. The crank-shaft is rotated by means of a gear 31 (Fig. 3) meshing with a pinion 32. The pinion is fixed upon a power-shaft 33 journaled in the frame of the machine below the crank-shaft 29.

Upon each end of the shaft is a pulley 34 which normally rotates freely upon the shaft. The clutch by which each of these pulleys may be connected with the power-shaft to rotate the latter, need not be particularly described, as it is of a well known type, it comprising the usual operating finger or lever 36, which co-operates with a cone 37 free to slide upon and to rotate with the power-shaft. In the position of the parts as shown in Fig. 3, the clutch at the left hand end of the shaft is out of operation, but when the cone 37 is moved to the left upon the power-shaft the clutch is thrown into operation and connects the pulley with the power-shaft. The clutch-cone of each clutch is operated by means of a forked shipper lever 38, which is fixed to a rock-shaft 39 journaled at the base of the frame of the machine.

All of the parts above described are in duplicate in the illustrated machine, which is of the usual twin form, so that while one pair of sole pressing instrumentalities is subjecting a shoe-sole to pressure, the operator may occupy the interval in removing and replacing the work between the other pair of sole pressing instrumentalities.

The two driving clutches are thrown alternatively into operation, however, by a single treadle mechanism which is operable in opposite directions. To this end the two shipper-levers 38 are connected by a rod 40 (Figs. 1 and 3) which has threaded extremities passing loosely through openings in the

levers. Nuts 44, adjustably mounted on the threaded portions of the rod 40, are adapted to engage the inner sides of the levers, so that one lever or the other is thrown in a direction to operate the corresponding clutch, according to the direction of movement of the rod. The rod is actuated by means of an arm 41 pivoted to the rod and extending upward from a rock-shaft 42 (Fig. 2) journaled at the base of the frame 75 of the machine. At the forward end of the rock-shaft 42 is a treadle 43 (Fig. 1), which extends on opposite sides of the shaft so that it may rock the shaft in one direction or the other, according as the operator 80 presses upon one end or the other of the treadle.

In order to guard against carelessness on the part of the operator and render it impossible for both clutches to be thrown into operation at once, nuts 45 are mounted upon the threaded extremities of the rod 40 outside of the shipper levers 38. The space between these nuts and the levers is sufficient to permit one lever at a time to be thrown into position to operate the corresponding clutch, but it is impossible for both levers at once to be in clutch operating position. To hold both clutches normally out of operation, the shipper-levers are connected by a spring 46 (Fig. 3) which tends to draw them both into normal inoperative position. It is thus necessary for the operator to maintain one end of the treadle in depressed position so long as the pressing instrumentalities of either side of the machine are to be held in operative position.

In connection with the clutch-mechanism just described, the machine is provided with a brake which is adapted to arrest the movement of the actuating mechanism immediately upon the release of either clutch through which the machine is being driven. To this end the crank-shaft 29 is provided with a brake-drum 47 (Figs. 3 and 4) on each side of the gear 31, and these brake drums are engaged simultaneously by a bifurcated brake-shoe 48. The brake-shoe has an upwardly extending stem 49 which is guided in a yoke 51 constituting a part of 105 the frame of the machine. A compression spring 52 surrounding the stem 49 normally presses the brake-shoe downward into operative engagement with the two brake drums.

To raise the brake into inoperative position when either clutch is in operation, levers 53 are pivoted upon shafts 54 at each side of the brake-shoe, the inner end of each lever 53 being articulated with the brake-shoe by means of a screw 55 (Fig. 4) engaging an opening in the end of the lever. Upon each shaft 54 is also pivoted a lever 56 provided at its inner end with an adjustable screw 57 (Fig. 3) adapted to engage the lever 53 when the outer end of 125

the lever 56 is depressed. Each lever 56 is connected, by a rod 58, with an arm 59 fixed on the shipper lever rock-shaft 39 which is below it. The arrangement just described 5 is such that when the shipper lever 38, as shown in Fig. 3, is swung to the left to throw the corresponding clutch into operation, the arm 59 pulls downward on the rod 58 thus causing the corresponding screw 57 of the 10 lever 56 to engage and raise the lever 53, and thus to raise the brake-shoe from the brake-drums and permit the crank-shaft to be rotated freely from the clutch-mechanism through the gears.

15 When a clutch is thrown into operation, as above described, the toggle 24—25 is moved toward a straight-line position, thereby raising the bed 23 and the form until the form engages the sole of the lasted shoe 20 on the jack. As soon as such engagement occurs, the continued movement of the bed causes the jack to rise, while at the same time the sole is subjected to a pressure due to and regulated by the weight of the jack 25 and the degree of compression of the springs 16.

The upward movement of the cross-head 5 is employed to actuate the automatic devices for throwing the clutch out of operation to discontinue the upward movement of the form. To this end each cross-head is provided with a bracket 60 (Figs. 1 and 2), and rods 61 are pivoted at their lower ends to the levers 56, while the upper ends of the 30 rods pass loosely through holes in the brackets and are provided with adjustable nuts 62. Each nut 62 is so adjusted that, upon the upward movement of either cross-head as just described, the bracket 60 engages the 35 nut and thus raises the rod 61 and draws the lever 56, to which it is connected, upward. This movement of the lever 56 throws the corresponding clutch out of operation automatically, and at the same time 40 permits the spring 52 to again cause the brake-shoe to engage the brake-drums, thereby at once arresting the movement of the actuating mechanism and also preventing return movement of the mechanism 45 under the influence of the downward pressure on the form and the bed.

50 After the automatic operation just described, the machine remains at rest with one pair of pressing instrumentalities in operative engagement with a shoe sole until the operator throws the treadle in the opposite direction to throw the other clutch into operation. As shown in Fig. 2, the two 55 pulleys at the opposite ends of the power shaft are driven by belts 63 and 64, of which the latter is a crossed belt, and as both belts are connected with the same source of power (not shown), the pulleys are rotated constantly in opposite directions. When, therefore, the position of the

treadle is reversed by the operator, as just described, the power-shaft at once moves in the opposite direction to the first movement described, thereby lowering the form which was previously raised and raising the other 70 form into operative position. This alternate operation of the two sides of the machine is thus continued indefinitely, the duration of the pressing operation depending upon the operator, while the degree of pressure to 75 which the work is subjected while governed automatically is the same for each shoe.

It will be obvious that as the upward movement of the bed and the form terminates automatically when the cross-head has 80 been raised and the springs 16 compressed to a predetermined extent, the pressure to which the work is subjected is invariable and does not depend upon the size of the last or of the shoe. As the movement of the 85 pressing mechanism is always arrested automatically after the form has moved through whatever distance may be necessary to produce the predetermined effect, all vertical adjustment of the pressing instrumentalities 90 is thus rendered unnecessary in changing from one style or size of shoe to another, after the machine has once been set to produce a predetermined pressure upon the work.

95 While the invention has been described as embodied in a sole pressing machine of a particular type, it will be obvious that the invention is not limited to machines of this type or to the details of construction 100 and operation hereinbefore particularly described and illustrated in the accompanying drawings, but that it may be embodied in various other forms, within the nature of the invention as it is defined in the following claims.

105 What is claimed as new is:—

110 1. A sole pressing machine, having, in combination, coöperating sole pressing members, one of said members being yieldingly supported against the pressure of the work, mechanism for moving the other member toward said yielding member, and means operating in untimed relation to the relative movement of the pressing members to 115 automatically arrest the operation of said mechanism and hold said members in pressure position when said yielding means has yielded a predetermined degree.

120 2. A sole pressing machine, having, in combination, a shoe supporting jack, a sole pressing form, a spring for supporting said jack against the pressure of the work, mechanism for moving said form through a variable distance toward the jack, and means 125 connected with the jack, and actuated through the yielding movement thereof, to interrupt the operation of said mechanism automatically and hold said jack and form in pressure position upon the attainment of 130

a predetermined degree of pressure upon the work.

3. A sole pressing machine, having, in combination, a yieldingly-mounted shoe 5 supporting jack, a form, mechanism for moving the form positively toward the jack through a variable distance, and means connected with and actuated by the jack for interrupting the operation of said mechanism and holding said jack and form in pressure position when the jack yields through a predetermined distance to the pressure of the work.

4. A sole pressing machine, having, in combination, a yieldingly-mounted shoe supporting jack, an adjustable spring for supporting the jack against the pressure of the work, a form, mechanism for moving the form toward the jack through a variable 20 distance, and means connected with the jack for interrupting the operation of said mechanism and holding said jack and form in pressure position when the jack yields, through a predetermined distance, to the 25 pressure of the work.

5. A sole pressing machine, having, in combination, coöperating sole pressing members; a source of power, a train of mechanism connecting one of said pressing members and said source of power, having a definite limit of extent of movement, for moving one of said members toward the other; and automatic means for disconnecting said train of mechanism from its source 30 of power to stop the advance of the moving member short of its limit of extent of movement, and for causing a dwell of said members in pressure position, after a predetermined amount of pressure has been applied 35 to the sole.

6. A sole pressing machine, having, in combination, two coöperating sole pressing members, and means for producing a continuous relative approach movement of 45 said members in the same general direction first through an indeterminate distance by which the work is engaged and then through a predetermined distance by which the work is compressed.

50 7. A sole pressing machine, having, in combination, coöperating sole pressing members, mechanism having a definite limit of extent of movement for moving one of said members toward the other, automatic means 55 for interrupting the advance of the moving member short of the limit of its extent of movement after a predetermined amount of pressure has been placed on the work, and a plurality of means independent of each 60 other by which the amount of pressure may be predetermined.

8. A sole pressing machine, having, in combination, coöperating sole pressing mem-

bers, one of said members having a pressure stroke movement throughout its limit of 65 travel toward the other, a source of power, a train of mechanism connecting said source of power and said last mentioned member through which pressure is exerted on the sole, and means to automatically disconnect 70 said train of mechanism from said source of power to vary the distance of travel of said member, dependent upon variations of thickness of the work held on the other member, whereby a uniform predetermined 75 amount of pressure is given to the sole regardless of its thickness.

9. A sole pressing machine, having, in combination, coöperating sole pressing members, mechanism having a definite limit of extent of movement for moving one of said members toward the other, a thrust spring for yieldingly holding said other member, automatic means for interrupting the advance of the moving member short of the 80 limit of its extent of movement, after a predetermined amount of pressure has been placed on work held on said other member, and means for predetermining the pressure comprising an adjustment for the thrust spring and devices to vary the travel of the 85 moving member.

10. A sole pressing machine, having, in combination, coöperating sole pressing members including a sole pressing form and a sole support; a source of power for operating said sole pressing members, a train of mechanism connecting one of said pressing members and said source of power through which the pressing members are relatively moved 95 to exert pressure on the sole; and means, operating in untimed relation to the cycle of operation of the machine, for disconnecting said train of mechanism from its source of power upon the attainment of a predetermined pressure on the sole.

11. A sole pressing machine, having, in combination, coöperating sole pressing members including a sole pressing form and a sole support; mechanism for relatively moving said members; a spring adapted to be compressed during such movement to exert pressure on the sole; and means operating in untimed relation to the cycle of operation of the machine for stopping the relative sole pressing movement of the support and form upon a predetermined compression of the spring, said means acting to hold the spring to the degree of compression attained at the moment the movement of the pressing members ceases.
